UNITED STATES PATENT OFFICE

JOSEPH STONE, OF BESSEMER, ALABAMA

CONTROLLING MECHANISM FOR MOLD-RAMMING MACHINES

Application filed August 15, 1928. Serial No. 299,765.

This invention relates to improvements in connection with the mold ramming machine patented by me on March 8th, 1927, No. 1,620,406. The improvements constituting 5 the subject matter of the present application relate more particularly to the automatic controlling mechanism, by means of which the side peans or rammers and the butt rammers are set in operation, permitted to make 10 a predetermined number of strokes, and are then stopped.

In the accompanying drawings,

Fig. 1 is a side elevation of the machine of my prior patent, with the improvements 15 of the present application incorporated therein.

Fig. 2 is a detail view of one of the stop discs, hereinafter described.

Fig. 3 is a fragmentary vertical section, 20 illustrating one of the stop discs and associated parts,

Fig. 4 is a detail sectional view of one of the pawls, hereinafter described.

Fig. 5 is a fragmentary plan view of a 25 portion of the driving mechanism,

Fig. 6 is a sectional view of the clutch and brake mechanism, hereinafter described, and

Figs. 7 and 8 are side and end elevations 30 of rammers, hereinafter described.

And Figs. 9 and 10 are detail front and plan views, respectively, of the control levers and associated parts, hereinafter described.

Like numerals designate corresponding 35 parts in all of the figures of the drawing.

In the drawings 5 designates a machine such as is illustrated in my prior patent. Side rammers 6 and 7, and butt rammers 8 40 are operated by cranks 9, 10 and 11, from transverse shafts 12, 13 and 14. These shafts are, in turn, driven through large gear wheels 15, 16 and 17, from a main longitudinal driving shaft 18. So far, the structure described is substantially like that of my prior patent. However, in the prior patent, the large gear wheels for driving the 45 transverse shafts 12, 13 and 14 were not fast upon said transverse shafts, but were 50 clutched thereto at the proper time by spe-

cial clutches. According to the present construction, these individual clutches for the several gear wheels are discarded together with their more or less complicated actuating mechanisms, and a much more compact, 55 economical and reliable structure is substituted therefor.

According to the present invention, the driving motor 19 drives through pinion 20 and silencer gear 21 to a main driving gear 24. My improved clutch mechanism is mounted directly upon the drive shaft 18. The gear 24 is free upon said shaft, and drives the shaft 18, when a clutch collar 25 is shifted toward the left in Fig. 6, and into 65 engagement with the gear 24. At this time, clutch collar 25 and gear 24 rotate together, carrying with them a sleeve 26, upon which the clutch collar is splined at 27, said sleeve, in turn, being keyed to the shaft 18, at 28. 70 It is clear that rotation of the shaft 18 will cause the gear wheels 15 and 16 to turn, because they mesh with pinions 29 and 30, upon the ends of the shaft 18, and that this rotation of the gears 15 and 16 will bring 75 about an actuation of the side rammers or peans, in the manner disclosed in my aforesaid prior patent. That is to say, the rotation of the shafts 12 and 13 will, through the cranks 9 and 10, and connecting links 30 80 and 31, impart a reciprocation to the shanks 6 and 7, of the side rammers. It will further be clear that if the clutch collar 25 be held against turning, that the parts normally driven thereby will likewise be held 85 against movement. Consequently, movement to the right, in Fig. 6 of the collar 25, will cause its engagement with the brake drum 32, which is supported in a fixed bearing collar 33, and when the clutch collar 25 is engaged with the brake drum, the brake is applied to the shaft 18, and to the parts normally driven thereby. In like manner, if a clutch collar 34, (see Fig. 6), be shifted to the right to bring it into engagement with 90 the gear 24, rotation will be imparted to the clutch collar, and to a sleeve 35, upon which said clutch collar is splined. This sleeve carries a bevel pinion 36, which constitutes the driving element of the gear 17, transverse 95 100

shaft 14, and the butt rammers connected therewith. If the clutch collar 34 be shifted to the left, in Fig. 6, it will be brought into engagement with the brake drum 37, which is fixed in a bearing collar 38, and when in this latter position, clutch collar 34, sleeve 35, pinion 36, and the parts driven thereby, are braked. To bring about the shifting of the collars 35 and 34 at the proper time, shifting levers 39 and 40 are pivoted at 41 and 42, the upper ends of said levers being provided with yokes 43 and 44, of a conventional nature, which engage the collars 34 and 35. Stop discs 45 and 46 are mounted upon the crank shafts 12 and 14. These stop discs are provided with notches 51 and 52, which coact with pawls 53 and 54.

The levers 39 and 40 may be grasped and actuated by hand, but I prefer to employ a single actuating member for these levers, consisting of a lever 40^a, which is pivoted at 40^b and carries a grooved disc 40^c, said grooved disc receiving the confronting edges of both of the levers 39 and 40. Thus, if the handle constituted by the lower portion of 40^a be swung in one direction, the disc 40^c will thrust against one of the levers, and if the handle be swung in the other direction said disc will be thrust against the other of said levers.

In the operation of the machine, the lever 40 is first moved to throw the collar 25 into engagement with gear 24. This sets the side rammers in operation. It also sets in operation a timing disc 90, which is carried by a gear wheel 91, that meshes with a pinion 92 on the crank shaft 13. Lever 40 is held in its thrown position by the engagement of a tooth 92^a carried by said lever, with the teeth 93 of the latch lever 94, that is pivoted at 95, and has its inner or free end connected by a link 96, with an arm 97. This arm 97 is fast upon a shaft 99, which passes through the frame 5 of the machine. Upon its inner end this shaft carries an upstanding lever 100, that is pivotally connected to a rod 101. A spring housing 102 contains a spring 103 which acts to thrust the rounded head 104, of rod 101, into a recess 105 of the timing disc 90. When this recess, or notch, 105 is in alignment with the head 104, the spring 103 acts to raise the toothed lever 94, but after the timing disc has started to revolve, and the notch is out of alignment with the head, the spring 103 is held in compressed condition and the lever 94 is held down, so that its teeth 93 will engage the latch, bolt or tooth 92^a, and hold the lever 40 in its thrown position until the timing disc has made a complete revolution, and the notch 105 again comes into alignment with head 104. Since the gear 91 is much larger than the pinion 92 it follows that the side rammers may make quite a number of strokes before the timing disc will have made a com-

plete revolution. The movement of the lever 40, as previously described, acted through a link 56, crank arm 57, and rock shaft 58 (see Figs. 1, 3 and 4) to rock the pawl 54 out of the notch 52 of the stop disc or shaft 12. The movement of the handle 40, which drew upon the link 56, as described, placed a spring 60 under tension, said spring bearing between a fixed member 61, on the frame, and a head 62 of a rod 63, that is pivoted at 64, to the lever 40. Consequently, after the timing disc 90 makes a full revolution, and the latch lever 94 is lifted, said spring 60 acts to move the lever 40 sharply back to its original or stop position. This return movement of the lever 40 acts to move the collar 25 into engagement with the brake drum 32, where it remains until the lever 40 is again positively actuated by hand to set the side rammers in operation. The return movement of the lever 40 acts through rod 56 and the parts to which it is connected, to throw the pawl 54 into the path of movement of the shoulder 52^a, formed by the notch 52, said pawl then acting as an abutment against which the stop disc comes to rest, thus insuring that the momentum of the parts will be checked at exactly the same point in their travel each time, and consequently, insuring that the side rammers will come to a position of rest in their elevated positions. This insures against the possibility of the side rammers coming to rest in their lowermost positions, where they would be in the way of the butt rammers when the latter begin to operate. The butt rammer operating shaft 14 is then set in operation by a manipulating handle 40^a to throw the lower portion of lever 39 to the left, in Fig. 1. This throws the upper portion of said lever toward the right and moves collar 34 into engagement with gear 24. As previously described, this drives shaft 14 through gear 17 and pinion 36. Operation of the butt rammers continues for a predetermined number of strokes, or until timing disc 110 which is driven by pinion 111 and gear 112, from shaft 14, has made a complete revolution.

The function of the timing disc 110 is the same, with respect to shaft 14, which drives the butt rammers, as that of the timing disc 90, with respect to shaft 13. That is to say, it holds the latch lever 94^a down, and in engagement with a latch, bolt or pin 92^a, to thereby hold the lever 39 in its thrown position until the timing disc has made a complete revolution. The movement of the lever 39 to thrown position acted through link 70, crank arm 71, rock shaft 72, to throw pawl 53 out of engagement with the notched portion of the stop disc 45. When the timing disc 110 has made a complete revolution and the plunger 104^a snaps back in the recessed portion of said timing disc, the lever 94^a is

lifted out of engagement with the latch bolt 92^a, and the lever 39 is returned to its former position. Under the action of a spring 74, which bears between a fixed member 75 of the frame, and the head 76, of a rod 77, that is pivoted at 78 to the lever 39, the return of the lever 39 to its original position acts through links 70 and associated parts, to again throw the latch 53 into the notched portion of the stop disc 45, where said latch acts as an abutment to insure that the butt rammers will be brought to a position of rest in elevated position. The return of the lever 39 to its former position also moves the collar 34 into engagement with the brake drum 37, to thereby bring the parts promptly to rest. The pawls 54 are cushioned by blocks of rubber 54^a, or equivalent elements, which are seated in crank sleeves 54^b, that are carried by the respective rock shafts 58 and 72. To prevent the pawls from accidentally leaving these sleeves they are traversed by pins 80, which move in slotted portions 81, of the sleeves 54^b.

In Figs. 5 and 6, I have illustrated a manner of separately connecting the peans or rammers proper to the shanks, by which they are carried. I find it of advantage to make the actual ramming elements 65 separable from the shanks 6^a, and to do this, I provide two-part heads 6^b—6^c upon the shanks, together with through bolts 66 to clamp the two-parts 6^b—6^c tightly together. Such clamping action binds these parts upon studs 67 of the ramming elements proper. This construction may be utilized for either the butt rammers or the side rammers.

Any desired means may be employed for driving the conveying system of the machine, such, for example, as the bevel gear connections A, B and C and pinion D meshing with gear 24. The particular means for securing this drive are not of the essence of the invention since many ways may be devised for securing the desired result.

It is to be understood that the invention is not limited to the precise construction set forth, but that it includes within its purview whatever changes fairly come within either the terms or the spirit of the appended claims.

Having described my invention, what I claim is:

1. A machine of the character described, comprising butt rammers and side rammers, an operating shaft for each set of rammers, a timing element for each of said shafts driven in unison therewith, a motor, a driven element actuated by said motor, brake elements associated with said driven element, an operating element for the side rammer shaft and an operating element for the butt rammer shaft, means for engaging the driven element with the operating element of the butt rammer shaft, and means operable when

the timing element of the butt rammer shaft has moved a predetermined distance for disconnecting the operating element of the butt rammer shaft from the driven element, and bringing it into engagement with the brake elements.

2. A machine of the character described, comprising butt rammers and side rammers, an operating shaft for each set of rammers, a timing element for each of said shafts driven in unison therewith, a motor, a driven element actuated by said motor, brake elements associated with said driven element, an operating element for the side rammer shaft and an operating element for the butt rammer shaft, means for engaging the driven element with the operating element of the butt rammer shaft, a manually operable lever serving as the actuating means for said engaging means, and means under control of the timing element of the butt rammer shaft for moving said lever to disconnect the operating element of the butt rammer shaft from the driven element and for bringing said shaft into connection with the brake elements.

3. A machine of the character described, comprising butt rammers and side rammers, an operating shaft for each set of rammers, a timing element for each of said shafts driven in unison therewith, a motor, a gear wheel actuated by said motor, brake elements associated with said gear wheel, an operating element for the side rammer shaft, an operating element for the butt rammer shaft, and means for engaging the driven element with either of the said operating elements, and means controlled by the timing element of the so engaged operating element for disconnecting said driven element from said operating element, and engaging it with the corresponding brake element.

4. A machine of the character described, comprising butt rammers and side rammers, an operating shaft for each set of rammers, a timing element for each of said shafts driven in unison therewith, a motor, a loose driven gear operated by said motor, an operating element for the side rammer shaft, an operating element for the butt rammer shaft, and means for engaging either of said operating elements with said loose gear wheel.

5. A machine of the character described, comprising butt rammers and side rammers, an operating shaft for each set of rammers, a timing element for each of said shafts driven in unison therewith, a motor, a loose driven gear operated by said motor, an operating element for the side rammer shaft, an operating element for the butt rammer shaft, means for engaging either of said operating elements with said loose gear wheel, and means under control of the respective timing elements for disconnecting the re-

spective operating elements from the loose gear.

6. A machine of the character described, comprising butt rammers and side rammers, an operating shaft for each set of rammers, a timing element for each of said shafts driven in unison therewith, a motor, a main drive shaft for actuating the butt rammers, a gear wheel driven by the motor and loosely mounted upon said shaft, a sleeve engaged with the main drive shaft, a clutch collar engaged with said sleeve and adapted to engage said loose gear, a fixed brake element adapted to be engaged by said clutch collar, a second sleeve engaged with the butt rammer shaft, a clutch collar adapted to connect the second sleeve with the loose gear, and a brake element adapted to be engaged by said clutch collar.

7. A machine of the character described, comprising butt rammers and side rammers, an operating shaft for each set of rammers, a timing element for each of said shafts driven in unison therewith, a motor, a main drive shaft for actuating the butt rammers, a gear wheel driven by the motor and loosely mounted upon said shaft, a sleeve engaged with the main drive shaft, a clutch collar engaged with said sleeve and adapted to engage said loose gear, a fixed brake element adapted to be engaged by said clutch collar, a second sleeve engaged with the butt rammer shaft, a clutch collar adapted to connect the second sleeve with the loose gear, a brake element adapted to be engaged by said clutch collar, independent manually operable levers for shifting said clutch collars, and means under control of the timing elements for locking said levers in the position in which the clutch collars are engaged with the loose gear.

8. A machine of the character described, comprising butt rammers and side rammers, an operating shaft for each set of rammers, a timing element for each of said shafts driven in unison therewith, a motor, a main drive shaft for actuating the butt rammers, a gear wheel driven by the motor and loosely mounted upon said shaft, a sleeve engaged with the main drive shaft, a clutch collar engaged with said sleeve and adapted to engage said loose gear, a fixed brake element adapted to be engaged by said clutch collar, a second sleeve engaged with the butt rammer shaft, a clutch collar adapted to connect the second sleeve with the loose gear, a brake element adapted to be engaged by said clutch collar, independent manually operable levers engaged with the clutch collars for shifting the same, spring means tending to move said levers to throw the clutch elements out of engagement with the loose gear, and into engagement with the brake elements, locking means for holding the levers in the position where the clutch col-

lars are engaged with said gear, means under control of the timing elements for releasing said locking means, and spring means tending to move the levers to braking position.

9. A machine of the character described, comprising butt rammers and side rammers, an operating shaft for each set of rammers, a rotative notched timing disc for each of said shafts driven in unison therewith, a motor, a main drive shaft for actuating the butt rammers, a gear wheel driven by the motor and loosely mounted upon said shaft, a sleeve engaged with the main drive shaft, a clutch collar engaged with said sleeve and adapted to engage said loose gear, a fixed brake element adapted to be engaged by said clutch collar, a second sleeve engaged with the butt rammer shaft, a clutch collar, adapted to connect the second sleeve with the loose gear, a brake element adapted to be engaged by said clutch collars, spring means tending to move said levers in one direction, pawls engageable in the notches of said discs connected with said levers and acting to hold said levers in thrown position except when the pawls are in the notches of the timing discs.

In testimony whereof I affix my signature.
